UNITED STATES PATENT OFFICE.

JUDSON A. DeCEW, OF NEW YORK, N. Y., ASSIGNOR TO PROCESS ENGINEERS, INCORPORATED, OF NEW YORK, N. Y., A CORPORATION OF NEW YORK.

METHOD OF MAKING EMULSIONS.

Application filed April 26, 1920, Serial No. 376,660. Renewed May 1, 1923.

To all whom it may concern:

Be it known that I, JUDSON A. DeCEW, citizen of the Dominion of Canada, residing at New York city, in the county of New York and State of New York, have invented certain new and useful Improvements in Methods of Making Emulsions, of which the following is a specification.

In the process of sizing paper various methods have been employed in the diluting of the rosin soap used for this purpose, which methods are more or less suitable to the kinds of rosin size being used.

When a rosin soap is used which contains free rosin dissolved therein, it is very difficult to dilute this size in a large volume of water, either hot or cold, without separation of the free rosin taking place, the combination not being directly soluble in an aqueous liquid of high dilution.

The most careful method of diluting any such substances as above described, with water, would be to start with a small quantity of size at a boiling temperature and with rapid stirring, add hot water slowly without affecting the stability of the compound.

This method, however, is not practicable in paper mill practice owing to the large quantity of material used and the slowness of the operation.

I have therefore, devised a method of progressive dilution by means of hot water which is added at various stages in the diluting process so that after the size is dissolved in the first quantity of hot water, it will come in contact with second and subsequent quantities of hot water, etc., until it reaches a stage of dilution where it can be chilled and stabilized with cold water without any separation or decomposition taking place.

A method of carrying out this process is to allow the hot size to pass into the pipe where it comes in contact with a small stream of hot water, where agitation takes place as the materials commingle and as the mixture flows along the pipe, is further diluted by a second stream of hot water also at a high temperature.

Such a device may be illustrated in the accompanying drawing in which 1 indicates a reservoir of size 2 having an outlet pipe 3 connecting by means of an elbow 7 with a horizontal pipe 4 communicating with a

tank 5 of cold water 6. 7 indicates an elbow between the pipes 3 and 4 and into this elbow 7 enters a pipe 8 of hot water which pipe terminates in a nozzle 9. 10 indicates a second hot water pipe entering the pipe 4 and terminating in a nozzle 11 and 12 indicates a third hot water pipe entering the pipe 4 terminating in the nozzle 13, the nozzles 9, 11 and 13 all being directed toward the cold water tank 5. The pipes 3, 8, 10 and 12 of course may be suitably controlled by valves. In the drawing, the various pipes have indications of steam arising therefrom. This is not actually the case but it is to indicate that the pipes are hot. In operation, the size 2 coming down the pipe 3 comes in contact with hot water from the nozzle 9 and is somewhat diluted. As it progresses, it comes in contact with the hot water from the nozzle 11 or it is further diluted and as it progresses again, it is still further diluted by the hot water from the nozzle 13. Then it emerges into the cold water 6 for stabilizing the emulsion.

By these successive stages of dilution, a similar condition is obtained to that in which hot water is stirred slowly into the thick size but inasmuch as it takes place in a pipe and the action is continuous, the time of dilution is short and it is simpler in action and capable of better control.

In addition to the above, if the hot water is caused to be the impelling force and moves in the direction of the flow of the size within the pipe, then there will be variations of pressure within the pipe length where solution is taking place inasmuch as the pressure will be least at the point where the force of the stream of water exercises a pull on the stream of size.

The alternation of pressure increases the agitation of the mixture and also the rate of solution for the hot size comes in contact with water at a low pressure which is suddenly increased.

The ratio of solution can also be increased and the efficiency improved by successively raising the temperature of the water as the dilution progresses as I find that the critical solvent temperature rises with dilution.

The most efficient method therefore, is to bring the hot size in contact with a small quantity of hot water and subsequently dilute it with small additions of hot water of

higher temperature, the temperature being increased with the dilution until it is discharged into cold water for stabilization.

What I claim is:

- 5 1. A method of diluting rosin size containing free rosin which consists in mixing hot size with hot water within a conduit in various distinct stages of progressive dilution and then discharging the size into cooler water.
- 10 2. A method of diluting hot rosin size containing free rosin which consists in passing the hot size through a conduit into cold water and in the passage therethrough

partially diluting it in successive distinct stages with hot water which flows continuously into contact with the hot size with which it blends and increases the dilution.

3. A method of diluting hot rosin size containing free rosin, which consists in bringing the size into contact with hot water within a pipe under steps of successive stages of increasing and decreasing pressure, and then discharging the size into cooler water.

In testimony whereof I affix my signature.

JUDSON A. DECEW.
